UNITED STATES PATENT OFFICE.

CLARENCE P. DAVEY, OF MARION, INDIANA, ASSIGNOR TO DELTA ELECTRIC COMPANY, OF MARION, INDIANA, A CORPORATION OF INDIANA.

SPOTLIGHT.

Application filed June 26, 1924. Serial No. 722,435.

To all whom it may concern:

Be it known that I, CLARENCE P. DAVEY, a citizen of the United States, and a resident of Marion, in the county of Grant and State 5 of Indiana, have invented certain new and useful Improvements in Spotlights, of which the following is a full, clear, and exact description.

The invention relates to spot-lights of the 10 type adapted to be manipulated on the outside of the vehicle from the inside thereof. Its object is to provide an improved spotlight of this type which can be easily installed, is simple in construction and can be 15 easily operated to project a column of light in substantially all directions.

The invention consists in the several novel 20 features hereinafter set forth and more particularly defined by claims at the conclusion hereof.

In the drawings: Fig. 1 is a side elevation 25 of a spot-light embodying the invention, showing it secured in the lower rail of a wind-shield frame, parts being shown in section. Fig. 2 is a vertical longitudinal section, the lamp being broken away. Fig. 3 is a front elevation, the incandescent lamp and reflector being omitted from its supporting bracket. Fig. 4 is a detail of one of the 30 clamping plates used in securing the device to the wind-shield frame. Fig. 5 is a detail perspective of the bearing sleeve which extends through the frame. Fig. 6 is a section on line 6—6 of Fig. 2. Fig. 7 is a section on line 7—7 of Fig. 1.

The invention is exemplified in a lamp 35 comprising a reflector 9 provided with a marginal flange 10 in which a lens 11 is suitably held. A split ring extends around the flange 10 and the margin of the lens to hold 40 the latter in connected relation to the reflector. The central portion of the reflector 9 is provided with a rearwardly extending flange 13 which is pressed into interlocked 45 relation with a cylindrical sleeve 14. A lamp-socket 14^a is secured in said sleeve, and the base of an incandescent lamp 15 is removably held in operative position in the socket by a pin-and-slot connection 15^b. 50 Sleeve 14 is held in the tubular portion 17' of a lamp-supporting bracket 17 by means of a set-screw threaded to the bracket. The rear end of the tubular portion of bracket 17 is closed, as at 17^b. Bracket 17 is prefer- 55 ably formed of a strip of sheet metal bent to

form the tubular portion 17' and members extended downwardly to form an arm 18. A sleeve 36 extends through a hole bored in the lower rail 37 of a wind-shield frame. The front portion of said sleeve is disposed 60 outside of the vehicle and is there provided with an enlarged portion 45 terminating at its front end in a shoulder 46. A collar 50 extends and is rotatable around the enlarged portion 45 of sleeve 36 and is preferably 65 formed of sheet metal bent to form a tubular portion 50^c and lugs 50^a, which are spaced apart and constitute a forwardly extending arm 51. The lamp-supporting bracket 17 is pivotally supported by a pivot 52 supported 70 in said arm 51. Clamping plates 38 and 39 are elongated laterally and have their ends shaped to conform to the front and rear faces of the wind-shield rail 37 and provide additional bearing surfaces for the sleeve 36. 75 Plate 39 is provided with lugs 40 fitting in recesses 41 in the enlarged portion 45 of sleeve 36 to lock the sleeve against rotation in the wind-shield frame. The sleeve 36 is held against longitudinal movement by a 80 nut 43 which is screw-threaded to a thread on the rear portion of said sleeve. A lock washer 42 is interposed between said nut and clamping plate 38. Collar 50 fits between clamping plate 39 and shoulder 46 on sleeve 85 36. A bolt 50^b extends through lugs 50^a to clamp the cylindrical portion 50^c with greater or less force of collar 50 around the sleeve to frictionally hold the collar against 90 rotation with the force desired and to correspondingly hold the lamp-supporting bracket 95 17 against such accidental rotation.

A hollow shaft 20 extends longitudinally through sleeve 36 and is slidable therein. The front end of said shaft is provided with 95 a fork 21 to which arm 18 is pivotally connected by a pin 22 which passes through holes in the fork and a curved slot 19 in the lower end of said arm, so that the lamp-carrying bracket, which is pivotally supported 100 at 52, may be rocked in the plane of arm 18 or radially with respect to shaft 20 by the longitudinal movement of said shaft. The inner end of sleeve 36 is split longitudinally at 36' and screw-threaded, and a nut 44, with a 105 tapered female screw-thread fitting the thread 36', is adapted to adjustably compress the split end of sleeve 36 to frictionally hold the shaft 20 against longitudinal movement in the sleeve. By adjusting nut 110

44, the frictional grip of shaft 20 may be varied to suit the individual users and to assure the holding of the shaft against movement resulting from the vibration of the vehicle. The frictional retardance to the rotation of collar 50 may be varied by the adjustment of nut 43 for the same purpose.

The inner end of the shaft 20 is provided with a handle 23, whereby it may be shifted 10 longitudinally or rotated. The inside of this handle is provided with a chamber 26, in which is disposed a switch which is adapted to be manually operated from the inside of the vehicle. This switch comprises a pair 15 of separate spring terminals 28, 29 mounted on an insulating block 27. Contact 29 is connected to the lamp-socket 14^a in the sleeve 14 by a flexible conductor 32 which passes through hollow shaft 20 and through the 20 back of the bracket 17. The other contact 28 is connected to a conductor 33 which is suitably connected to a battery, as well understood in the art. A slidable contact button 31 is mounted in a cap 30 which closes 25 the rear end of handle 23. This handle is removably secured to shaft 20, so that the shaft 20 and sleeve 36 may be passed through the wind-shield before the handle is attached. The handle is connected to said shaft by 30 means of a stud 24 and a clamping collar 24^a. The front end of the handle is split, as at 23^a, so it can be pressed firmly around said shaft. Said collar also holds the stud 24 so its inner end will be held in a hole 20^a 35 in the hollow shaft. This collar is adapted to be clamped around the handle by a bolt 24^c. When the collar is removed, the stud can be inserted through the handle and into hole 20^a after the shaft 20 and sleeve 36 40 have been passed through the wind-shield frame.

The lamp and its supporting bracket 17 can be adjusted radially of shaft 20 by shifting the handle 23 forwardly or backwardly 45 by means of the pivotal and sliding connection 22, 19, the bracket swinging around the pivot 52. The bracket 17 and lamp are bodily and rotatably adjustable by the rotation of handle 23, this movement being effected through shaft 20 which will rotate the bracket 17 and collar 50 together when the handle is rotated, the collar 50 being rotatable around the sleeve 36. By means of these two adjustments, the lamp may be 50 universally adjusted to project a column of light to any desired point or in any desired direction within the range for which it is designed.

When the lamp is to be installed, it is only 60 necessary to drill a hole in the wind-shield rail 37 for the sleeve 36. With the handle 23 removed from shaft 20 and clamping-plate 38, washer 42 and nuts 43, 44 removed from sleeve 36, the latter may be inserted into the 65 wind-shield from the front thereof, while

the collar 50, bracket 17 and shaft 20 remain in connected relation. Next, the clamping plate 38, washer 42 and nuts 43, 44 will be placed in operative position, whereupon the sleeve will be properly mounted in the frame. After the sleeve 36 and shaft 20 therein have been installed, handle 23 will be secured to the shaft 20 by placing the stud 24 in its operative position and clamping the split collar 24^a in position around the front end 75 of the handle.

The invention exemplifies a spot-light for vehicles which can be produced at a low cost, is universally adjustable and which can be conveniently operated from the inside of the 80 vehicle.

The invention is not to be understood as restricted to the details set forth, since these may be modified within the scope of the appended claims, without departing from the 85 spirit and scope of the invention.

Having thus described the invention, what I claim as new and desire to secure by Letters Patent, is:

1. In a spot light for vehicles, the combination of a sleeve extending through the windshield frame, plates around the sleeve for engaging the inner and outer curved sides of and conforming to the frame, a shoulder on said sleeve, means cooperating 90 with said shoulder for clamping said plates against the frame, means between said shoulder and one of said plates to hold the sleeve against rotation, a shaft rotatably mounted in said sleeve, a lamp mounted on the outer end of said sleeve and connected to rotate bodily with said shaft, and a handle on the inner end of said shaft whereby the shaft 95 may be rotated.

2. In a spot light for vehicles, the combination of a sleeve extending through the windshield frame, plates around the sleeve for engaging the inner and outer curved sides of and conforming to the frame, a shoulder on said sleeve, means cooperating 100 with said shoulder for clamping said plates against the frame, a lug and slot connection between said shoulder and one of said plates to hold the sleeve against rotation, a shaft rotatably mounted in said sleeve, a lamp mounted on the outer end of said sleeve and connected to rotate bodily with 105 said shaft, and a handle on the inner end of said shaft whereby the shaft may be rotated.

3. In a spot light for vehicles, the combination of a sleeve extending through the windshield frame, means for holding said sleeve against longitudinal and rotary movement in said frame, a shaft slideable and rotatable in said sleeve, means for adjustably clamping the inner end of said sleeve against the shaft to frictionally hold said shaft against longitudinal and rotary movement in said sleeve, a lamp mounted on the outer 115 120 125 130

end of the sleeve, a connection between the shaft and the lamp for swinging and bodily rotating the lamp, and a handle on said shaft whereby the shaft may be rotated to

5 rotate the lamp or shifted longitudinally in the sleeve to swing the lamp.

4. In a spot light for vehicles, the combination of a sleeve extending through the windshield frame, means for holding said sleeve against longitudinal and rotary movement in said frame, a shaft slideable and rotatable in said sleeve, said sleeve being split at its inner end, means on said end for clamping it against the shaft to frictionally hold said shaft against longitudinal and rotary movement in said sleeve, a lamp mounted on the outer end of the sleeve, a connection between the shaft and the lamp for swinging and bodily rotating the lamp, 20 and a handle on said shaft whereby the shaft may be rotated to rotate the lamp or shifted longitudinally in the sleeve to swing the lamp.

5. In a spot light for vehicles, the combination of a sleeve extending through the windshield frame, means to secure said sleeve against movement in the frame, a shaft slideable and rotatable in said sleeve, a lamp mounted to swing relatively to and to 25 rotate bodily with said shaft, a connection between the shaft and the lamp for swinging and rotating the latter, a handle at the inner end of said shaft, a stud extending through said handle and into a hole in the shaft for positively locking the handle and shaft together and against relative rotative and longitudinal movement, and a clamp extending around the handle and the stud.

6. In a spot light for vehicles, the combination of a sleeve extending through the windshield frame, means to secure said sleeve against movement in the frame, a shaft slideable and rotatable in said sleeve, a lamp mounted to swing relatively to and 40 to rotate bodily with said shaft, a connection between the shaft and the lamp for swinging and rotating the latter, a handle at the inner end of said shaft having a split inner end, a stud extending through the in-

ner end of said handle and into a hole in 50 the shaft for positively locking the handle and shaft together and against relative rotative and longitudinal movement, and a clamp extending around said inner end of the handle and the stud to press the handle 55 around the shaft and to secure the stud in its operative position.

7. In a spot light for vehicles, the combination of a sleeve extending through the windshield frame, plates around the sleeve 60 for engaging the inner and outer sides of said frame, a shoulder on the outer end of said sleeve, means for holding said sleeve against longitudinal and rotary movement in said frame, a shaft slideable and rotatable in said sleeve, a collar rotatably mounted around the shoulder and provided with pivot lugs, a lamp supporting bracket pivoted to said lugs, a lamp secured in said bracket, a bolt and slot connection between 70 the shaft and said bracket for swinging the latter radially and for rotating it, and a handle on the inner end of the shaft whereby the shaft may be shifted longitudinally and 75 rotated.

8. In a spot light for vehicles, the combination of a sleeve extending through the windshield frame, means for holding said sleeve against longitudinal and rotary movement in said frame, a shoulder on said 80 sleeve, a shaft slideable and rotatable in said sleeve, a collar rotatable around the shoulder formed of a plate of metal fitting around said sleeve and extended to form pivot lugs, means for adjustably clamping 85 said lugs together to vary the frictional engagement between said collar and shoulder, a lamp supporting bracket pivoted to said lugs, a lamp secured in said bracket, a bolt and slot connection between the shaft and 90 the bracket for swinging the latter radially and for bodily rotating it, and a handle on the inner end of the shaft whereby the shaft may be shifted longitudinally and rotated.

Signed at Marion, in the county of Grant 95 and State of Indiana, this 20th day of June, 1924.

CLARENCE P. DAVEY.
